UNITED STATES PATENT OFFICE.

BENJAMIN C. POLE, OF CAMDEN, NEW JERSEY.

STEAM-ENGINE.

SPECIFICATION forming part of Letters Patent No. 371,214, dated October 11, 1887.

Application filed December 20, 1886. Serial No. 222,081. (No model.)

To all whom it may concern:

Be it known that I, BENJAMIN C. POLE, an engineer, a citizen of the United States, residing at Camden, in the county of Camden and 5 State of New Jersey, have invented certain new and useful Improvements in Steam-Engines; and I do hereby declare the following to be a full, clear, and exact description of the invention, such as will enable others skilled 10 in the art to which it appertains to make and use the same.

My invention relates to engines using steam or vapor to operate a cylinder and piston and gain a rotary motion, and the nature thereof 15 is in constructing an engine upon one main shaft, making that shaft support the engine, and at the same time be the moving shaft of the engine, to give out the power of the engine; furthermore, in construction of a system 20 of steam or vapor valves, together with conveyers to supply this engine with steam, the system of valves to operate the cylinder, and an elastic stop-action to give direction for the revolution of the engine.

25 The invention consists in construction in and to the vapor conveyers, permitting the introduction of vapor from a stationary point, and the delivery of the exhaust to a similar stationary point, yet permitting the conveyers to 30 revolve with the cylinder construction of the engine. These conveyers are provided with slide or rotating valves for governing the induction and eduction of the steam or vapor to the cylinder of the engine.

35 The invention also consists in a segmental-shape cylinder. This cylinder is provided with regular valves capable of working any vapor, and the cylinder is provided with a piston and piston-rod ring having suitable 40 packing; also, construction to connect this piston-rod ring with the other working parts of the machinery to carry out the object of the invention; also, in adapting a straight cylinder and piston with guides and connecting- 45 rod, to operate in such a manner as to carry out the object of the invention, and in providing this mechanism with a stop-action to give the direction of the revolution of the engine either forward or backward.

50 The invention also consists in counterbalancing the above set-forth cylinder system, or

in duplicating by another cylinder, causing the cylinders to counterbalance each other.

In all the figures the same letters refer to the same parts.

By reference to the drawings, Figure 1 is a part sectional side elevation of my engine, showing the upper part of the supporting-shaft of the engine in full lines and the upper part of the engine above the same in section. 55 The parts of the engine that come below the shaft are shown in side elevation. Fig. 2 is a sectional side elevation of the engine on line *xx* of Fig. 1, showing the segmental cylinder with its side plate removed; also, each half of each cylinder-head removed, thereby showing the piston rod ring and piston in elevation and the connection of the crank-wheel in elevation; also, the central support for the guide of the piston-rod ring in section, the main-shaft of the 60 engine in section, one counterbalance weight in side elevation; also, the elastic stop of the engine in elevation and the bed-plate of the engine in section. Fig. 3 is a side elevation of the engine, looking from the position of letter A, and shows the carrier-stop fly-wheel that is the means of giving revolution to the fly-wheel on main shaft of the engine; also, the elastic stop-action for giving direction for the revolution of the engine. Fig. 4 is a side elevation of the face of one of the steam-conveyers, as shown in Fig. 1, and shows the outside strap for holding the two faces of the steam-conveyers together, shows the port-openings for the steam and exhaust, also the 65 bolts at the side of the strap to enable its being placed on the steam-conveyer in halves. Fig. 5 is a side elevation of the divided strap as set forth in Fig. 4 and is without the steam-conveyer. Fig. 6 is a part sectional side elevation of the upper half of a steam-conveyer, showing the induction and eduction openings for the steam and exhaust, also part of the rounding space allowed for the main shaft of the engine to go through which carries or supports the steam-conveyer. Fig. 7 is a sectional side elevation of an equivalent steam-conveyer which is provided with annular steam-conveying rings. (Shown in sectional elevation.) These rings are provided with stuffing-boxes and followers and bolts to hold the same for the purpose of packing the steam- 75 80 85 90 95 100

rings. The carrying main shaft to the engine is shown through the center of the steam conveyer in elevation, and there is bolted on the outer end of the steam-conveyer and shown in section a rotating valve. This section is taken on line $z z$ of Fig. 8. Fig. 8 is a cross section on line $y y$ of Fig. 7, showing the steam divisions for the live steam and exhaust in the steam-conveyer. Fig. 9 is a cross-sectional elevation of the annular steam-conveying rings on line $w w$ of Fig. 7, with the steam-conveyer in dotted lines. Fig. 10 represents a cylinder of square form with the two heads removed, and shows the piston-rod ring in section, the packing-followers of the piston in elevation, and the side plate of the cylinder bolted thereto; also central hub to carry the cylinder. Fig. 11 is a sectional side elevation of my engine adapted to operate with the ordinary steam-cylinder, slide-valve, guides, and side connecting-rods to the crank-wheel in accordance with the object of my invention. Fig. 12 is a sectional side elevation of a direction-stop for giving direction to the revolution of the engine, being a roller-stop action provided with an inclined plane to resist going in a wrong direction. Fig. 13 is a part sectional side elevation of a direction stop in which a cog-and-pinion action is used instead of a roller, as shown in Fig. 12. Fig. 14 is a sectional side elevation of a direction-stop in which a rubber roller is used which is provided with a projection bolted into a stop-strap for giving direction to the revolution of the engine.

35 The construction of the steam or vapor conveyers of this engine enables me to use cylinder constructions which are adapted to use steam-gas, vapor of soda-ammonia, high or low pressure, compressed air, or bisulphate of carbon.

40 I do not confine myself to any class of vapor for operating this invention.

The nature of this invention is to impart rotary motion to a shaft that is the supporting and driving shaft of the engine, and this is done by a system of cylinders that are arranged on the periphery or rim of a wheel or drum. Said cylinders are provided with reciprocating pistons. Vibrating or slide valves are regularly packed to prevent the escape of steam, and the direction of the revolution of the engine either backward or forward is controlled by a system of stop and slip actions; also, the power of the engine is imparted to the shaft of the engine by a second system of stop and slip actions. The action of the piston of the engine is well understood in the ordinary engine, and in my invention the piston and the movement of the piston-rod ring move at the proper time the cylinder as well and its connections, so that the cylinder, piston, piston-rod-ring valves, and all the connections of the engine steam-regulators, together with the steam-conveyers, will all join at the proper time in making the general revolution of the engine, the whole construction revolving on the driving and supporting shaft, and only

prevented from going backward or in an undesired direction by the stop-action, which is connected to the foundation or bed-plate of the engine. The stop and slip and slip-action is used for the reverse action of my engine. In large engines both the cylinder as well as the crank-wheel will have a direction-stop action, preventing any motion of the mass of the cylinder construction in the wrong direction, and in the engine presented the situation of this double stop is shown in dotted lines in Fig. 1; and, further, notwithstanding the reciprocating action of the piston design of this engine, the general revolution of all the construction on the main driving and supporting shaft is obtained.

In my engine a wheel, G^3 , with additional construction, performs the duty of the crank-axle, and the hub of this wheel g' rests upon the main driving-shaft C of the engine B between the cylinder E and fly-wheel $K K$. The fly-wheel $K K$ is keyed onto the main driving-shaft C , and a construction—a stop and slip action—is attached on the side of the crank-wheel E^3 , and on the top of the wheel $K K$ is the construction—the stop-and-slip action K —which projects from the side of the wheel E^3 . This stop K is the means by which the power of the engine is applied to operate and drive the main driving and supporting shaft of the engine. The crank-wheel E^3 also serves another purpose, that of carrying the direction-stop strap E^4 , that is—the construction that is used to give the direction for the revolution of the engine forward or backward.

The letter A is placed on the drawings at Fig. 1 and indicates the side of the engine that Fig. 3 represents. The engine B is mounted on journals $B' B^2$, suitably supported either by a bed-plate or hung by hangers from the floor above, and has a main driving and supporting shaft, C , provided with the fixed collar C' near the middle thereof. This collar C' is for the purpose of holding the drum D and D' in position on the shaft C , and to prevent the drums sliding on the shaft wearing-washes $d d'$ are interposed between the collar C' and the drums D and D' . This construction permits the drums D and D' to revolve freely on the shaft C ; but they are prevented from moving along the shaft by sliding. On the drum D is a counter-drum, D^2 , facing inward, and this counter-drum is the rest and guide for the central sleeve, F , of the piston-rod-ring constructions G . Bolted to the drums D and D' is the cylinder E of the engine. This cylinder E is in the form of a segment of a circle one way and square, with rounding corners, in the opposite direction or cross-section. (See Fig. 10.) The cylinder is inclosed by five pieces—to wit, four divided pieces forming the two heads on either end, of similar construction, provided with stuffing-boxes divided through the middle, and a side piece, $e e$, closes the side, making five pieces. The heads of the cylinder $e^2 e^3$ are divided parallel with the side plate of the cylinder, cutting through

the center of the stuffing box, and the followers e^4 e^5 for the packing of the stuffing-box are also divided in the opposite direction to the cylinder-heads e^2 e^3 . This construction 5 permits packing the stuffing-boxes and the removal of the cylinder-heads notwithstanding the piston-rod ring G is a flat ring in form. When the cylinder-heads are removed from the cylinder, the piston of the piston rod ring 10 can be packed. The cylinder E can be cast with a boss in lieu of the drums D and D' , as is shown in Fig. 10.

At either end of the cylinder E and in both of the two pieces that form the cylinder-heads—15 that is to say, the halves nearest to the side plate, e e , of the cylinder—there are provided openings to attach the steam-pipes to allow the steam to enter for the use of the cylinder. This pipe e^6 is attached to a valve, e^7 , that can 20 have a slide or vibrating plug. It is understood that there are two of these valves e^7 . For the purpose of having steam or vapor right up at the plug or slide valves e^7 , to be turned on into the cylinder, and by the action of the 25 plug or slide valves return the steam-exhaust through another channel side by side with the steam, there is provided a construction I term a "conveyer," having channels to separate the induction from the eduction vapor. 30 Valve e^7 connects with the steam-conveyer H . They are faced off and steam-fitted and the two faces brought together. There are in these faces sets of ports or openings coming opposite each other, one set of ports at a greater 35 distance outward from the center line than the other set, one being within the other with reference to the center line. The steam-conveyer H revolves, and the steam conveyer H' is stationary and receives the steam in the 40 channel h and passes it through the center ports, h' , to the conveyer H , which has a similar channel and set of ports, and this channel delivers the steam at the plug or slide valve e^7 . The plug or slide valve is to alter the 45 stream of steam from pressure to exhaust in the manipulation of the piston in the cylinder and return the exhaust through a channel and set of ports, h^2 . By this construction there is a perfectly free passage for the steam and exhaust between the two conveyers H and H' and one stream of steam is inside of the other. The faces of these conveyers H and H' are held 50 together by a strap, h^{15} , which surrounds them and presses on a projection, h^{16} and h^{17} , on conveyers H and H' , holding them together.

Fig. 6 shows that the openings for the channels for the induction and eduction of steam in the conveyer H are side by side, to carry out the system of having two steam-channels brought up to the plug or slide of valve e^7 . (Shown in Fig. 8.) In this conveyer H^2 is an equivalent system to the conveyers H and H' , and is cast in one piece, channels and all, instead of two pieces, as in the drums H and H' . 65 By making the conveyer H^2 in one piece together with the channels the valves e^7 are bolted directly to the steam-carrier H^2 . This

construction H^2 is to revolve with the cylinder construction of the engine and is upon the main shaft C . This construction H^2 is more 70 fully shown in part sectional views on the drawings by Figs. 7, 8, and 9. The views show the means of supplying the steam for the induction and eduction, and I will describe the construction of the carrier H^2 . There is a round- 75 ing and turned-up and finished drum, h^8 , and the main shaft C passes through the center of this drum at h^4 , and the pipe h^5 prevents the escape of steam through the opening for the main shaft C . This pipe h^5 is provided with 80 division-walls h^6 , extending up and connected to the drum h^8 , and this construction forms the channels h^7 and h^8 , having openings h^9 , one into channel h^7 and the other in the channel h^8 ; but farther along the drum h^8 are the means of 85 communication with the channel h^7 and h^8 . Enveloping these openings h^9 and surrounding the drum h^8 are placed two annular steam-conveying rings, H^3 and H^4 . They are placed side by side of each other on the steam-conveyer 90 H^2 , and are provided with packing-rings h^{11} , to prevent the escape of steam. There are the well-understood sloping faces h^{10} for the packing, together with the follower-rings h^{11} , and these rings are suitably tightened on the packing by bolts h^{12} . These bolts h^{12} are passed through sleeves, so as to prevent the escape of steam through the openings necessary for the bolts h^{12} , and thus is prevented all side escape of 95 steam or vapor, and both annular steam-conveying rings H^3 and H^4 are alike.

To illustrate the invention, the induction and eduction of the steam are noted at letters h^{13} and h^{14} on annular steam-conveying rings H^3 and H^4 . The annular steam-conveying rings H^3 and H^4 , 100 with their attachments for packing, are stationary, while the steam-conveyer H^2 , with its drum h^8 , revolves with the valve e^7 , pipes e^6 , and cylinder E on drums D and D' . The steam enters the annular steam-conveyers H^3 at h^{13} , 105 passes through the openings h^9 into the channel h^7 , and is delivered to the plug or slide of valve e^7 . The continuation of these channels h^7 and h^8 up to the plug or slide of valve e^7 is shown in dotted lines, and by the operation of the 110 plug of the valve e^7 the exhaust is returned along the channel h^8 , passes out through the opening h^9 to the annular steam-conveying ring H^4 , and out at h^{14} to the atmosphere or otherwise. Construction H and H' or H^2 can 115 be used with the segmental form of cylinder or the straight-line cylinder with a slide-valve and its connections, as shown in Fig. 11.

The piston-rod ring G of the engine is provided on one side with spokes g , and these connect with the central sleeve, F . This sleeve F forms the guide for the piston-rod ring G to rest upon, and vibrate upon being supported by the counter-drum D^2 of the drum D . To the piston-rod ring is bolted the connection G' , 125 and this takes hold of the crank-pin G^2 of the crank-wheel G^3 , and this crank-wheel G^3 rests upon its hub g' , and is free on main shaft C . The crank-wheel G^3 carries the strap 130

wheel G^4 , which is the direction mechanism of the engine B—that is, the mechanism by which the direction for the revolution of the engine, either backward or forward, is governed and operated. This strap is provided with the extension G^5 and rests upon the spring construction G^6 , which rests or is attached to the foundation or bed-plate or support of the engine B. The construction of this direction-strap G^4 is better shown in Fig. 12; and it is there shown that the stop and slip L is a roller and has the incline L L, which converges inward to the wheel G^3 ; also, the additional rollers, L' L'', are to carry the strap G^4 ; and should the crank-wheel G^3 stop and attempt to go in the wrong direction, then the roller L will be jammed by the incline L L and against the wheel G^3 , and stop the wheel G^3 by the strain of the roller L transmitting this jamming wrench to the extension G^5 , and from thence on to the spring G^6 to the foundation G^7 of the engine, thus stopping the crank-wheel G^3 from going in the wrong direction, and, upon the wheel G^3 starting forward again, this spring will return the strain used in stopping wheel G^3 , and the roller L will free itself when the crank-wheel G^3 starts to revolve in the desired direction. The strap G^4 rolls easily by roller L' on the crank-wheel G^3 . The stop-action shown in dotted line G^7 represents a stop-action for the cylinder construction of the engine B, and is of like construction to that hereinbefore described for the crank-wheel G^3 , the cylinder construction being provided with a wheel-ring to engage with a similar strap construction, G^4 , to act as stop and give direction for the revolution of the engine. This construction is only used for large engines of great power.

The equivalent stop-and-slip action shown by Fig. 13 is as follows: The crank-wheel G^3 is provided with teeth, and pinion-wheels intergear with G^3 for a stop action. Small pinion-wheels g^6 g^8 g^9 are carried by a carrier, G G, sliding on the wheel G^3 . This carrier G G is equivalent to the strap G^4 , as heretofore described. To attach the pinion-wheels g^6 g^8 g^9 to the carriers G G, there are provided two straps, g^5 , on either side of the carriers, with the bolt g^7 , that passes through the straps g^5 and pinion-wheel g^6 , and carrier G G, holding the construction in the carrier G G. In the straps g^5 are a pair of springs, g^{12} , which go up to the bearings that carry pinion-wheel g^8 . The springs are for the purpose of allowing the pinion g^8 to come back along the slot into gear with the pinion g^6 , and form a lock when the wheel G^3 is to be stopped going backward, but will permit it to run free in the desired direction. The extension g^{10} on the straps g^5 is attached to a lever for the purpose of a reverse action for the wheel G^3 . The pinion g^8 is held by a bracket, g^{11} , coming down from the top of the carrier G G; but should the crank-wheel G^3 go backward, then the pinion-wheel g^8 will fall into gear with the pinion-wheel g^6 and form a lock upon the

crank-wheel G^3 . The carrier G G cannot go back, and is not allowed to move in an undesired direction. The pinion-wheel g^9 runs on the wheel G^3 , and is attached by the bracket g^{11} to the carrier G G. The links g^6 by the extension g^{10} can draw over the wheels g^6 g^8 and cause a lock to be formed with the wheel g^9 .

In Fig. 14 the rim of the crank-wheel G^3 runs against an elastic roller, L', and this has the extension L⁵ and the cleat L⁶, which retains the roller-extension L⁵, so that when the crank-wheel G^3 shall attempt to go in the wrong direction, then the roller L' squeezes on the case G G' and against the wheel G^3 , forms a jam, and prevents backward motion, as has been heretofore described.

The piston-rod ring G is provided with the piston G⁸, capable of being packed by packing, which is held in by followers g² g³, and the piston-rod ring G is of a flat section, as shown in Fig. 10. On the crank-wheel G^3 , and attached to it at the side thereof, is the roller stop-and-slip action K. This rides on the fly-wheel K K of the engine B. The fly-wheel K K is keyed on the main shaft C of the engine B. This stop-and-slip action K is provided with recesses K' and roller K² and incline K³, and is made to grasp the fly-wheel K K under the rim at K'. When the crank-wheel G^3 , to which the carrier and stop-action K is attached, shall revolve in the desired direction, the fly-wheel K K will be carried or revolved along with it; but should the fly-wheel K K move faster than the wheel G^3 , then the slip of the stop-action K will permit the wheel G^3 to go slower than the wheel K K, although both wheels may be going in the same direction. There can be two stops K on the fly-wheel K K. The cylinder E is counterbalanced; or two cylinders can be on one drum opposite to each other and counterbalance each other.

The operation of my invention is as follows: The steam is admitted through the steam-conveyers to the plug or slide of the valve e¹, and the spokes g of the piston-rod ring operate the lever T, moving the plug or slide of valve e¹ of the steam-conveyers, and the pressure of the steam on the piston and head of the cylinder causes the cylinder to revolve with all of its connections and move forward with velocity for its revolution. It is the weightiest part of the engine B. The crank-wheel G^3 is free to revolve in one direction only, and the piston moves along the prolongation of the cylinder by the movement of the cylinder itself, and the spoke g of the piston-rod ring G, at or near the end of the stroke, moves the lever T, and reverses the steam and opens the back-exhaust and impinges the steam into the cylinder at the opposite side of the piston, causing the steam that is between the piston and cylinder-head to form a cushion for the inertial velocity thus attained by the cylinder, its counter-weights and connections causing it to impart and expend the full value of this inertial velocity and carry around and revolve the piston-rod ring, the crank-

wheel, and the carrier on the fly-wheel, the fly-wheel, through the stop-action thereon, and the main driving-shaft of the engine, are all made to revolve in one direction, and this operation repeats. In this movement of the piston-rod ring with the cylinder is the power of this engine. In this engine should the resistance to the movement of the main driving-shaft C be so great as to stop the same, the action of the piston-rod ring, together with the cylinder construction, would be to continue to make their reciprocating action. Thus arrested, the cylinder would stop and fly back and make one-third of a revolution backward. The stop on the crank-wheel will receive the full strain of stopping this movement of the cylinder. Notwithstanding it would be cushioned by the change of the steam from one end of the cylinder to the other, the stop would compress the spring. The steam, continuing to act, would restart the cylinder to revolve, again go forward and make it expend its force (its inertial velocity) in the right direction, and through its mechanical connections, that operate on the driving-shaft, move it forward and the machinery to be driven by this engine. Should the driving-shaft of the engine, however, not be relieved of the excessive strain, but practically hold the cylinder from turning the main shaft, the cylinder would again fly back, repeat, and come up again, attempting to hammer along or around the driving-shaft of the engine, throwing out very great inertial strains. It is to prevent a very large cylinder making the back action that the double stop G G' is provided, as great weight being thrown backward would be dangerous.

I do not confine myself to any shape of cylinder or flat or round form of piston or piston-rod ring, or system to act as back-stops and slide-actions. These constructions will form subject-matter for application for other Letters Patent.

The governor U regulates the velocity of the engine. The pipe S is for the exhaust of the engines.

What I claim as my invention, and desire to secure by Letters Patent of the United States, is—

1. An engine provided with a cylinder, piston, and valve-action supplied with steam for the induction and eduction thereof, all supported on one main shaft, and construction to 55 make it revolve in a desired direction, substantially as and for the purposes set forth.

2. An engine provided with a revolving cylinder, piston, and valve, and operating action, together with induction and eduction, 60 steam conveyer and construction to make it revolve any desired direction, all supported on one main shaft, and a system of governing the speed of the same, substantially as set forth.

3. An engine having one central line of motion provided with a segmental or straight-line cylinder suspended from and by a line-shaft provided with a piston of suitable construction, with operating steam induction and eduction valves, and a means of supplying steam or vapor thereto, and for the operation of the 70 revolution of the whole engine direction-stops, substantially as and for the purpose set forth.

4. A roller stop-action engaging with the operating-wheels and crank and connected piston devices retained and carried by the engine, all supported on one main shaft and elastically held by the foundation of the engine to insure the revolution of the engine for the purpose of giving direction to the revolution of a system of cylinders, substantially as and 75 for the purposes set forth.

5. An engine provided with a pinion or an elastic stop-action to engage with the operating crank-wheel and piston devices or similar construction and held by the foundation of the 85 engine to insure the revolution of the engine in one given direction, all having a common center of motion, substantially as and for the purpose set forth.

6. A drum steam-conveyer provided with 90 face ports adapted to supply a stream of vapor in one direction, with a stream of vapor moving in an opposite direction, with one stream inside or at the side of the other, and mounted upon a central shaft, substantially 95 as and for the purpose set forth.

7. A cylindrical steam or vapor conveyer adapted to revolve and supply steam for the cylinder, and annular steam-conveying rings to operate on the revolving-cylinder conveyer, substantially as and for the purpose set forth.

8. An engine with a revolving cylinder, a reciprocating piston rod or piston-rod ring, and connecting-crank devices, all supported on 105 one main shaft, provided with a stop-and-slip action to give direction for the revolution of the engine, substantially as and for the purpose set forth.

9. An engine with a revolving cylinder, a reciprocating piston-rod or piston-rod ring, and connecting-crank devices, all supported on one main shaft, provided with a stop-and-slip action to give direction for the revolution of the cylinder, and a second stop-and-slip action to impart the power of the engine to the driving-shaft, substantially as and for the purposes set forth.

In testimony whereof I affix my signature in presence of two witnesses.

BENJAMIN C. POLE.
